FUEL HEATER FOR INTERNAL-COMBUSTION ENGINES

Charles F. Brookes, Toronto, Ontario, Canada

Application August 28, 1944, Serial No. 551,575

5 Claims. (Cl. 257—229)

1

The invention relates to improvements in fuel heaters for internal combustion engines as described in the present specification and shown in the accompanying drawing that forms a part of the same.

The main object of the invention is to provide simple and efficient means for heating the fuel to a high degree just prior to its entry into the carburettor whereby it will vaporise readily, thus assuring thorough combustion of the fuel, with the resulting advantages such as increased mileage per unit of fuel, elimination of carbon, and more efficient engine operation.

A further object of the invention is to provide a fuel heater having but a single connection with the exhaust manifold of the engine thus making it possible to readily incorporate said heater with the manifold, even in cases where, due to the confined grouping of engine parts about the manifold, no appreciable amount of such manifold is accessible.

Generally the objects of the invention are to provide an efficient fuel heater of simple and durable construction which can be produced at low cost.

The invention consists in the novel features of construction, arrangements and combinations of parts described in the present specification and more particularly pointed out in the claims for novelty following.

In describing the invention reference will be made to the accompanying drawing, in which:

Figure 1 is an interior plan view of the heating chamber with the top of the casing removed.

Figure 2 is a vertical sectional view through the structure shown in Figure 1 and the associated part of the exhaust manifold.

Figure 3 is a cross sectional view through an exhaust manifold of circular form showing a method of securing the heater to a manifold of such form.

Like numerals of reference indicate corresponding parts in the various figures.

Referring to the drawing the numeral 1 indicates the exhaust pipe of an engine, which has a flat top wall 2.

3 is the casing which provides the heating chamber through which the fuel pipe 4 is passed, said casing preferably being circular in plan, and consisting of a bottom and a circular side wall 50 and which is adapted to be closed at its top end by means of a cap 5.

The bottom of the casing 3 is provided with a central opening 6 around which is fitted a pipe 7 which extends outwardly a considerable dis-

2

tance and which is adapted to be inserted into the exhaust manifold 1 through a suitable opening through the top wall 2 of said manifold, whereby the heating chamber may be supported above the exhaust manifold.

The pipe 7 throughout a considerable portion of its length, particularly at, and above, the junction of said pipe with the apertured wall of the manifold is enlarged slightly and provided with external threads 8 whereby said pipe may be threaded into the opening in the top wall 2 and whereby a nut 9 may be threaded downwardly thereon into engagement with a suitably apertured block 10 which is suitably secured to the 10 said wall of the manifold, to firmly secure the pipe to the manifold. This pipe is preferably projected into the exhaust manifold to the extent that the lower end thereof will terminate slightly short of the wall of the manifold opposite to that 15 through which the pipe enters whereby to leave a space between the end of the pipe and the inner wall of the manifold for the direct passage of 20 some of the gases.

The pipe 7 is provided near its lower end in 25 the side thereof positioned in the path of the gases through the exhaust, with an inlet 11 through which the exhaust gases can pass upwardly into the casing 3, and said pipe is also provided on its opposite side with an outlet 12 through which the gases re-enter the exhaust 30 after circulation through the said casing.

The pipe 7 is divided throughout its length by a partition 13 which extends transversely in relation to the exhaust manifold and divides the 35 said pipe into an upward passage 14 through which the gases entering the inlet 11 are conducted into the heating chamber, and a downward passage 15 through which the gases from the said chamber flow and are permitted to re-enter the exhaust through the outlet 12.

The partition 13 extends upwardly into the casing 3 and terminates just short of the closure 5 and at least that part of said partition which is located within said casing is formed to provide a conduit 16 for the gases open at its top end, which latter is spaced but slightly from said closure whereby such closure will act as a baffle to disseminate the gases throughout the heating chamber.

The preferred method of providing the conduit 16 is by providing that portion of the partition 13 which is located within the casing, and if desirable that portion of said partition which is positioned above the exhaust manifold, with an extension 17 from one edge thereof bent to semi-

circular shape and secured along its edge to the said partition at or near the edge of the latter opposite to that from which said extension projects.

While the partitioning member is described hereinabove and shown in the drawing as being formed to provide the conduit as an integral part thereof, it is of course understood that such conduit may constitute a separate tube aligned with the top end of the inlet through the pipe 7 and suitably sealed against the escape of the heating medium into the casing except through the top end of said tube.

The fuel pipe 4, in which is interposed, at a point prior to its entry into the heating chamber, a suitable valve 18, enters the casing at a point near the bottom of said casing and spirals around the conduit 16 in outer and inner spaced coils and leads outwardly from the inner coil through a suitable opening in the wall of the casing substantially diametrically opposite the point of entry into the casing, and from whence it leads into the carburetor (not shown in the drawing).

In the operation of this invention a large proportion of the heated gases from the exhaust flow directly into the inlet 11 in the pipe 7 and are forced upwardly under pressure through the inlet side of said pipe and through the conduit 16 into the heating chamber where they circulate around the coiled fuel pipe and serve to heat the fuel in said fuel pipe to a high temperature, and are drawn by vacuum down the outlet side of said pipe 7 and pass through the outlet 12 into the exhaust manifold.

As the inlet to the pipe 7 is located in the side of said pipe directly in the path of the gases expelled into the exhaust under pressure from the engine it will be seen that the gases entering the inlet will be forced upwardly into the heating chamber under pressure. Furthermore the shape of the heating chamber and the substantially concentric positioning of the vertical conduit therein makes possible the accommodation within the chamber of the maximum amount of fuel pipe to a given area, and further provides for the maximum heat being applied to the fuel just prior to its exit from the heating chamber.

In Figure 3 the device is shown as being applied to an exhaust manifold of circular cross section, in which case an apertured adapter 19 having a semi-circular recess 20 in one face thereof adapted to conform to the peripheral contour of the manifold, and a flat top surface 21 adapted to conform to the flat face of the adjusting nut, is placed over the manifold with its aperture in alignment with the threaded opening in the manifold through which the pipe 7 enters said manifold, so that when the pipe 7 is threaded into said opening and the nut is turned down against the adapter the device will be securely locked to the manifold.

While the hereinabove described fuel heater has been shown and described as associated with the exhaust manifold of an engine it is of course to be understood that it can be incorporated with any other suitable means for supplying steam, hot water, hot air, etc. thereto.

While I have illustrated and described the present preferred forms of construction for carrying out my invention, these are capable of variation and modification without departing from the spirit of the invention. I, therefore, do not wish to be limited to the precise details of construction set forth, but desire to avail myself of such

variations and modifications as come within the scope of the appended claims.

What I claim as my invention is:

1. A heater for the fuel supplied to an internal combustion engine, comprising a casing closed at one end and having its other end provided with an opening concentric therewith, a pipe leading outwardly from said opening and adapted to be inserted in the exhaust manifold of said engine, said pipe having an inlet in one side thereof positioned in the path of the gases passing through said exhaust manifold and having an outlet for the gases diametrically opposed to said inlet, a partitioning member extending upwardly through said pipe into said casing and terminating slightly short of the closed end of the latter and dividing said pipe into two longitudinally extending passages whereby the hot gases entering said inlet are caused to flow upwardly into said casing through one passage and after circulating throughout the area of said casing will flow downwardly through the other of said passages to said outlet, said partitioning member throughout that portion which is located within said casing being formed to provide a conduit open at its top end whereby the gases are expelled at the top of said casing, and a fuel pipe passing through said casing and having that portion located within said casing coiled around said conduit whereby the fuel passing through said fuel pipe will be heated by the hot gases within said casing.

2. A heater as set forth in claim 1, in which said conduit is formed by an extension from one edge of said partitioning member bent to semi-circular shape in cross section at the side of said partitioning member at which said inlet is located and sealed to the said partitioning member and its lower edge sealing the casing against the escape of the heated gases thereinto at the bottom of said casing.

3. A heater for fuel supplied to an internal combustion engine, comprising a casing closed at one end and having an opening through the other end thereof, a pipe leading outwardly from said opening and adapted to be inserted in the exhaust manifold of the engine in the path of progress of the gases through said exhaust manifold, an apertured block secured to the wall of said manifold with its aperture aligned with the opening through which said pipe enters said manifold, a nut threading over said pipe into engagement with said block and securing said pipe to said manifold, said pipe having an inlet located within said manifold in the path of said gases and also having an outlet in substantially diametrically opposed relation to said inlet, a partitioning member separating the inlet side of said pipe from the discharge side throughout the length of said pipe, said partitioning member having a tubular extension projecting upwardly into said casing to a point near the closed end of the latter whereby the hot gases entering said pipe through said inlet will be carried upwardly and expelled through the top end of said tubular extension, and a fuel pipe passing through said casing and having that part thereof located within said casing coiled around said tubular extension.

70 4. A heater as set forth in claim 1, in which said fuel pipe extends in a series of turns around the inner periphery of the casing and is turned inwardly and extends around the said conduit in another series of turns and thence leads from the casing to the carburetor, whereby in its passage

through the casing the fuel is subjected to the greatest heat just prior to exit from the casing.

5. In a heater for fuel supplied to an internal combustion engine, a casing closed at its top end and having an opening in its lower end, a pipe leading outwardly from said opening and adapted to be inserted in the exhaust manifold of the engine, a partitioning member extending throughout the length of said pipe and dividing said pipe into two longitudinal passages leading respectively to and from said casing, said pipe having an inlet in one side thereof opposed to the

inlet end of said exhaust manifold and communicating with one of said passages, said pipe also having an outlet opposed to said inlet and communicating with the other of said passages, an open end conduit registering with the passage leading to said casing and extending upwardly within said casing and terminating in slightly spaced relation to the closed end of the latter, and a fuel pipe leading through said casing and having that portion thereof located within said casing coiled around said conduit.

CHARLES F. BROOKES.
